CORE COVERING APPARATUS

James P. Shorrock, Holyoke, Mass., assignor to
 B. F. Perkins & Son, Inc., Holyoke, Mass., a
 corporation of Massachusetts

Application June 8, 1935, Serial No. 25,639

5 Claims. (Cl. 117—34)

This invention relates to improvements in core-covering apparatus and is directed more particularly to improvements in apparatus for covering relatively fine cores such as rubber threads and the like with yarn of silk, rayon, composition, etc.

The principal objects of the invention are directed to the provision of improvements in core-covering apparatus of the type disclosed in U. S. Letters Patent to Raymond E. Getchell No. 1,970,228 of August 14, 1934.

According to one special feature of the invention an apparatus for covering cores is provided which by reason of its novel construction and arrangement is capable of covering very small cores of rubber or similar materials with yarn or various materials to produce covered cores which are uniform in all important respects.

In the covering of such cores as rubber threads in the smaller sizes it is necessary that the covering layers be wound thereon in a uniform manner and at a uniform tension thereby to produce a covered core which is properly balanced and uniformly covered.

According to this invention therefore in order to produce the desired results, the covering yarns are carried by spindles which are disposed within cups having travelers at their upper sides, the cups rotating with the spindles and yarn packages whereby the traveler rotates relative to the cup only to accommodate unwinding of the yarn from the package, thereby providing the desired tension for the yarn. In this way the yarn, where smaller sizes are concerned, is not subjected to undue tension while the windage is reduced, whereby uniform winding is facilitated and breaks and injury to the product are greatly reduced if not obviated.

According to a further feature of the invention, the apparatus is not only adapted to cover cores of the class referred to but, as distinguished from winding the finished core on a drum, means is provided to form the finished and covered core into the form of a skein. The skein is formed on a reel or skein-forming device which is frictionally driven and not only is it possible to produce a perfect skein which may be easily inspected and removed, but it is possible to temporarily release the skein-forming device from its driving connection to facilitate inspection of the yarn being led thereonto to determine its balance, etc.

Various and numerous other novel objects and advantages of the invention will be observed from the following description of the preferred form

thereof, reference being had to the accompanying drawings, wherein:

Fig. 1 is a sectional elevational view of the upper part of an apparatus embodying the novel features of the invention;

Fig. 2 is a sectional elevational view of the lower part of the apparatus, the said Figures 1 and 2 being a continuation of one another;

Fig. 3 is an end elevational view of a machine with parts broken away for clearness;

Fig. 4 is a plan view of the skein-forming part of the apparatus;

Fig. 5 is a sectional elevational view through one of the package cups;

Fig. 6 is a fragmentary elevational and sectional view on the line 6—6 of Fig. 5 to explain certain features of the invention; and

Fig. 7 is a sectional plan view on the line 7—7 of Fig. 5.

Referring now to the drawings more in detail the invention will be fully described.

In Figs. 1 and 2 there is shown an end frame 2. There are at least two of said end frames which are spaced apart and arranged to support the apparatus of the invention. A longitudinal shelf 4 extends between the end frames adjacent their lower sides and thereabove there is another similar member 6. Above the members there is a rail 8 and uppermost rail 10. These, of course, are suitably connected to the end frames to space and tie them together and provide a strong rigid structure.

Upper and lower spindle units indicated generally by 14 and 16 are provided, there being two units or a pair of units to one set. There may be as many sets of these units as may be desired along each side of the rails and it will suffice to merely explain the construction of one complete unit.

A lower shaft 20 is provided on which is an unwinding drum 22. The shaft 20 is driven by means as will later appear. An operating rod 24 is arranged for reciprocation up and down and its lower end carries a pair of spaced bracket members such as 26 having slots 28 on their outer ends.

A core carrier 30 which may be in the form of a spool has trunnions 32 in the slots of brackets 26. The core to be covered is wound on the barrel of the spool 30 and rests upon the unwinding drum 22 so that as the drum rotates the member 30 is rotated so that the core is unwound.

Lower and upper motors 34 are carried by the rails 6 and 8. Hollow spindles 36 extend upwardly from the motors so that a core C led from the

spool 30 extends through a lower guide 40 upwardly through the lower motor and its spindle and then upwardly through the upper motor and its spindle.

5 An upper rotatable shaft 44 extends between the end frames and it has fixed thereto a take-up drum 46 while spaced arms 48 thereabove are fixed to the rod 24. These arms 48 have slots 50 in the ends thereof. There is a lower roll 52 arranged to rest on the drum 46 and an upper roll 54 rests on the lower roll 52. Trunnions as shown are associated with the rolls 52 and 54 which rotate in the slots 50 of the brackets 48 to permit removal and insertion of the rolls 52 and 54 in 10 the said arms or brackets.

15 An operating lever 60 is pivoted at 62, preferably just below the longitudinal rail 8, and its end 64 is disposed between members 66 on rod 24. As the lever 60 is swung between the upper position shown and a lower position the rod is moved 20 upwardly. Reverse movements of the lever 60 will move the rod into reverse directions.

25 Brake levers 68 are associated with the motors 34 and when the rod 24 moves downwardly it acts on the levers 68 to release brakes associated with the motors. When the rod 24 moves upwardly levers 68 swing upwardly allowing a spring mechanism to automatically function to operate the 30 brakes associated with the motors after the manner described in the Getchell patent above referred to.

35 Yarn packages indicated by P in Fig. 5 have central cores 70' which slip over the spindles 36. Slots 72 in the lower ends of the cores receive driving pins 74 associated with the lower walls 76 of spindle cups 80. Extending upwardly from the lower walls 76 there are cylindrical side walls 78 forming the cups which are preferably relatively thin and made of relatively light material to reduce weight. Covers 80 are provided for the upper sides of the cups and these have inwardly extending parts 82 and downwardly extending peripheral flanges 84.

40 One or more pins such as 86 may be carried by 45 the flanges 84 and slots such as 88 are provided adjacent the upper edge of the side walls to receive the pins whereby the caps 80 may be removably associated with the cups.

45 A guideway 90 for a traveler is provided on the 50 covers 82 adjacent the upper ends of the package and a traveler such as 92 is movable therearound. The traveler being in the form of a ring or loop such as is usual in apparatus of this kind, is adapted to receive yarn from the packages.

55 Shafts 28 and 44 are driven in the following manner. Outside of one end flange 2 there are upper and lower gear boxes 100 and 102. A motor 104 has upper and lower shafts 106 and 108 60 all as shown in Fig. 3. The upper shaft carries a worm 110 in mesh with the worm gear 112 which is fixed to a shaft 113 of the gear box 100. The lower shaft 108 has a worm 120 in mesh with a 65 worm gear 122 of a shaft 124 and other gears 126 serve to operatively connect the shaft 28 with the shaft 124.

70 The gear arrangement referred to is arranged so that the lower shaft and upper shaft 44 are driven in such a ratio that the core when in the form of a rubber thread is subjected to a uniform constant tension or stretch as it is unwound by drum 22 and taken up by drum 46.

75 When the rod 54 is in its lower position, the yarn on the spool 30 is in contact with the un-

winding drum and the other roll 52 is in contact with the take-up drum which drums as stated being driven at the desired relative speeds will tension the core as may be desired. As the motors are operated to rotate their spindles and 5 cups connected therewith, the yarn packages are rotated with the spindles for winding the yarns thereof onto the core C, the yarns passing through the travelers are tensioned more or less according to the weight of the travelers.

10 Because the yarns as they extend from the packages to the travelers are disposed within the 15 cups rotating with the packages windage is largely obviated and by the reduction of the friction between the travelers and their guide rings, the 20 yarns are not unduly tensioned but are tensioned uniformly to the desired degree wherefore the 25 yarns are wound about the core uniformly. Guides 130 and 132 are provided to carry the yarn and their upper or outer ends are disposed above 30 the spindles to properly guide the core and its covering.

35 Brackets 140 carried by the upper rail 10 have outer spaced ends 142 as shown in Fig. 4. Rollers 144 are rotatable in the parts 142. A skein reel 150 has saddles 152 on the ends of arms 154 and a central shaft 156 thereof has on opposite ends 40 pulleys or rollers 158 which are adapted to rest on adjacent rollers 144.

45 The particular form of skein-forming device is 50 shown and described in my pending application Serial No. 25,640 filed June 8, 1935, but any skein-forming device may be used which is adapted to be supported and rotated by a pair of adjacent 55 rollers such as 144.

55 Pulley 160 is associated with pairs of aligned 60 rollers 144 and is driven by means of a belt 162 passing thereover and over pulleys 164 of shaft 166. As shaft 166 rotates, the pulleys 164 and belt 162 drive a pair of aligned rollers 144 and the 65 pulley 160 so that the skein-forming device is frictionally driven to wind up the covered core.

65 A traversing bar 180 has a guide for each skein-forming device such as 182 and this traverses back and forth to lead the yarn back and forth as it is 70 taken up by the skein-forming device.

75 A lifter or elevator 190 reciprocable up and down in the brackets 142 and disposed below the 80 rollers 158 of the skein-forming device is actuated by means of a rod 192 pivoted at 194 and 85 which has its end associated with the upper end of rod 24.

85 As the rod 24 is elevated the elevator 190 is moved upwardly to lift the skein-forming device 90 upwardly so that it is not frictionally rotated during the time the roll 52 is elevated from the take-up drum 46 and the supply spool 30 is elevated above the drum 32.

90 In the operation of the apparatus the core travels from the supply spool 30 upwardly through the spindles, over the take-up drum 46 and through the rollers 52 and 54 and onto the skein-forming device. The skein-forming device serves to take up the covered core while the motor spindles rotate to supply the covering, the core being tensioned all the while to the desired tension. During the operation of the apparatus it is possible since the skein-forming device is frictionally driven to rotate it in a direction opposed to its 95 winding direction so that a loop of the covered core may extend downwardly for inspection and other purposes. The loop may be taken up by turning the skein-forming device in its normal direction of rotation and when it is desired to stop 100

the machine the rod 24 is elevated. Thus by elevating the rod 24 the motor brakes function, and simultaneously the rod moves the supply spool 30 upwardly from the drum 22 and the roll 52 upwardly from the drum 46 and moving the skein-forming device upwardly so that it is no longer driven by the rolls 144. In this way all the parts come to rest simultaneously.

While I have described the invention in great detail and with respect to a preferred form thereof, it is not desired to be limited thereto since many changes and modifications may be made therein without departing from the spirit and scope of the invention. What it is desired to claim and secure by Letters Patent of the United States is:

1. The combination in apparatus of the class described of, coaxial hollow spindles, means for driving the same, means for feeding a core to said spindles, and means for winding up a core including, supporting rolls, means to drive one of said rolls, a skein reel having saddles and a roll at a side thereof resting on said rolls whereby the reel is supported by said rolls and frictionally rotated by said one roll, all adapted and arranged whereby an operator may grasp the reel to arrest its rotation or rotate it reversely to the normal direction of rotation.

2. In an apparatus for covering a core with yarn comprising in combination, co-axial upper and lower hollow spindles for yarn packages, means for driving the same, means for feeding a core to said spindles and means for winding a covered core into skeins as it comes from said upper spindles including, a plurality of supporting and driving rolls, means for driving certain of said rolls, a skein forming device having arms and saddles about which a covered core may be wound and rolls at the sides thereof for resting on said supporting and driving rolls whereby the skein device is supported and frictionally driven in one direction for skeining a core from said upper spindles and is adapted to be manually rotated in an opposite direction to unwind the covered core and provide a loop of covered core between said upper spindle and skein-forming device for inspection purposes.

3. In an apparatus for covering a core with yarn comprising in combination, co-axial upper and lower hollow spindles for yarn packages, means for driving the same, means for feeding a core to said spindles and means for winding a covered core into skeins as it comes from said upper spindles including, a plurality of supporting and driving rolls, means for driving certain of said rolls, a skein forming device having arms and saddle

about which a covered core may be wound and rolls at the sides thereof for resting on said supporting and driving rolls whereby the skein device is supported and frictionally driven in one direction for skeining a core from said upper spindles and is adapted to be manually rotated in an opposite direction to unwind the covered core and provide a loop of covered core between said upper spindle and skein-forming device for inspection purposes, the means for driving said rolls including driven members associated therewith, a drive shaft carrying driving members and connections between said members.

4. In an apparatus for covering a core with yarn comprising in combination, co-axial upper and lower hollow spindles for yarn packages, means for driving the same, means for feeding a core to said spindles and means for winding a covered core into skeins as it comes from said upper spindles including, a plurality of supporting and driving rolls, means for driving certain of said rolls, a skein forming device having arms and saddles about which a covered core may be wound and rolls at the sides thereof for resting on said supporting and driving rolls whereby the skein device is supported and frictionally driven in one direction for skeining a core from said upper spindles and is adapted to be manually rotated in an opposite direction to unwind the covered core and provide a loop of covered core between said upper spindle and skein-forming device for inspection purposes, and means for moving the skein-forming device away from said rolls.

5. In an apparatus for covering a core with yarn comprising in combination, co-axial upper and lower hollow spindles for yarn packages, means for driving the same, means for feeding a core to said spindles and means for winding a covered core into skeins as it comes from said upper spindles including, a plurality of supporting and driving rolls, means for driving certain of said rolls, a skein forming device having arms and saddles about which a covered core may be wound and rolls at the sides thereof for resting on said supporting and driving rolls whereby the skein device is supported and frictionally driven in one direction for skeining a core from said upper spindles and is adapted to be manually rotated in an opposite direction to unwind the covered core and provide a loop of covered core between said upper spindle and skein-forming device for inspection purposes, the said rolls being arranged in pairs and one each of said pairs constituting the driving rolls.
